UNITED STATES PATENT OFFICE.

MORRIS B. MOSER, OF WELLS, MINNESOTA.

BABBITTING MACHINE.

Application filed October 17, 1921. Serial No. 508,329.

To all whom it may concern:

Be it known that I, MORRIS B. MOSER, a citizen of the United States, residing at Wells, in the county of Faribault and State 5 of Minnesota, have invented certain new and useful Improvements in Babbetting Machines; and I do hereby declare the following to be a full, clear, and exact description of the invention, such as will enable others 10 skilled in the art to which it appertains to make and use the same.

My invention has for its object to provide a highly efficient and accurate babbetting machine intended for general use, but especially 15 adapted for use in forming babbitt bearings in the connecting rods of multiple cylinder combustion engines.

To the above end, the invention consists of the novel devices and combinations of devices hereinafter described and defined in 20 the drawings.

In the accompanying drawings, which illustrate the invention, like characters indicate like parts throughout the several 25 views.

Referring to the drawings:

Fig. 1 is a side elevation of the improved machine, on which is mounted a connecting rod for receiving a babbitt bearing, some 30 parts of the machine being broken away and other parts being indicated in different positions by means of broken lines;

Fig. 2 is a view partly in end elevation and partly in transverse vertical section taken on the line 2—2 of Fig. 1, on an enlarged scale, with some parts shown in different positions by means of broken lines;

Fig. 3 is a fragmentary plan view;

Fig. 4 is a view principally in longitudinal vertical section taken on the line 4—4 of Fig. 3, with the top and bottom core plates inverted in respect to their position shown in Fig. 2;

Fig. 5 is a view partly in end elevation and partly in transverse vertical section showing a modified form of mold and also showing a clamping attachment for the mold; and

Fig. 6 is a fragmentary plan view of the 50 parts shown in Fig. 5.

The babbetting machine illustrated includes a skeleton frame having substantially A-shaped end members 7 connected by upper side bars 8 and a bottom shelf 9. A

long narrow table 10 is mounted on the 55 frame end members 7 for angular lateral tilting adjustment by providing said table, at its ends, with depending lugs 11, which are pivotally connected to bearing brackets 12 on said frame end members by a long clamping rod 13 which extends through aligned bores in said lugs and bearing brackets, and is provided with a nut-acting hand wheel 14. To positively hold the lugs 11 in different adjustments on the bearing brackets 12, 60 said lugs and bearing brackets are provided with serrated surfaces 15 on their opposing faces.

A horizontal turntable 16, having hinged top and intermediate sections 17 and 18, respectively, is secured to the top of the table 10 at its inner end by a nut-equipped pivot bolt 19. The top section 17 is hinged at 20 to the turntable 16 and loosely rests on the head of the pivot bolt 19, and the intermediate section 18 is hinged at 21 to said top section 17 at a point diametrically opposite from the hinge 20. A set screw 22, having screw-threaded engagement with the top section 17, impinges against the intermediate 75 section 18 and adjustably supports said top section 17 therefrom. Overlying the table 10 is a track rail 23, square in cross-section and rigidly secured to a pair of laterally spaced transversely extended blocks 24, 80 which, in turn, are rigidly secured to the top section 17. The other or outer end of the track rail 23 is supported in the fork of a bifurcated bracket 25 attached to the outer end of the table 10. A hook-acting spring 90 26, attached to the bracket, (see Fig. 1), is arranged to releasably engage the track rail 23 and yieldingly hold the same on the bracket 25.

At the inner end of the track rail 23 is a 95 horizontal face plate 27 having a depending hub 28 mounted in a collar 29 rigidly secured to the upper ends of a pair of upright arms 30 having, on their lower ends, sleeves 31 secured to the ends of a horizontal cross-bar 100 32 by screw-threaded engagement. This cross-bar 32 is intermediately secured to the inner end of the track rail 23 by a nut-equipped stud 33. Thumb screws 34 prevent the sleeves 31 from turning on the cross-bar 32, and which cross-bar is provided with reduced end extensions 35, for a purpose that will presently appear. A set

screw 36, having screw-threaded engagement with the collar 29 and hub 28, prevents the face plate 27 from turning on said collar. On the upper surface of the face plate 27 are concentric work-positioning rings 37.

In Figs. 1 to 4, inclusive, the machine is shown adjusted and provided with the necessary mold for forming a babbitt bearing in the crank-receiving end α of a connecting rod y , and which end, as shown, comprises half sections connected by nut-equipped bolts α' . The other or wrist-pin-receiving end of the connecting rod y is indicated by the letter z .

In this adjustment of the machine, the mold includes a core sleeve, around which the connecting rod end α is positioned. The core sleeve 38 is secured to the intermediate portion of a spindle 39. The mold further provides upper and lower annular core plates 40 and 41, respectively, having axial openings through which the ends of the spindle 39 project. These core plates 40 and 41 are adapted to rest upon the ends of the core sleeve 38 and close the ends of the connecting rod end α , as shown in Fig. 4.

The lower end of the spindle 39 is removably mounted in a bushing 42 mounted in the hub 28 of the face plate 27 and held by the set screw 36 with the bottom core plate 41 supported on said bushing and the face plate 27. Removably mounted on the upper face plate 40 is a hopper flange or skinning cup 43 into which molten babbitt is poured, and from where it flows through apertures 44 in the top core plate 40 into the space between the core sleeve 38, connecting rod-receiving end α and top and bottom core plates 40 and 41. One of the faces of each core plate 40 and 41 is smooth and the other face thereof has formed therein an annular groove 45. When the faces of the core plates 40 and 41, having the annular grooves 45, are turned toward each other, as shown in Fig. 2, the babbitt bearing will be formed with beads which overlap the ends of the connecting rod end α . By inverting the core plates 40 and 41 to turn their smooth faces toward each other, as shown in Fig. 4, the babbitt bearing will be formed flush with the ends of the connecting rod end α .

The connecting rod end α is held by an upright spindle 46, which extends therethrough, as best shown in Fig. 1, and is of the same diameter as the wrist pin to which the connecting rod is to be applied. The lower end of the spindle 46 is removably mounted in a socket 47 having a base 48 provided with a pair of transversely aligned trunnions 49 journaled in upstanding bearings 50 on the sides of a traveller 51. This traveller 51 is in the form of a sleeve square in cross-section and slidably mounted on the track rail 23 for movement toward and from the spindle 39. By making the track

rail 23 and traveller square in cross-section, said traveller is held on the track rail 23 against turning movement.

To secure the spindle 46 in different angular positions in respect to the traveller 51 and parallel to the spindle 39, there is provided a pair of diametrically opposite lock nut equipped thumb screws 52, which have screw-threaded engagement with the base 48 on opposite sides of the trunnions 49 and impinge against the upper face of the traveller 51. A thumb screw 53, having screw-threaded engagement with the traveller 51 and arranged to impinge against the track rail 23, is provided for holding the traveller in different positions on said track rail.

To set the axis of the spindle 46 at predetermined different distances from the axis of the spindle 39 for holding the connecting rod y to receive a babbitt bearing in the end α , the axis of which is the correct distance from the axis of its end z , there is provided a square rotary scale bar 54 having in its edges notches 55 with any one of which a pointer 56 on the traveller 51 is arranged to enter by a springing movement. This scale bar 54 extends parallel to the track rail 23 and has, at its ends, trunnions 57 mounted in bearings 58 on one side of said table. In actual practice, the scale bar 54 will have indicated thereon, at each notch 55, an identification mark for assisting the operator in setting the spindle 46, for holding connecting rods to receive a babbitt bearing, the axis of which is the correct distance from the axis of its other end. These identification marks may be the names of the engine, or the automobile for which the connecting rods are intended, or they may indicate different lengths of connecting rods. A shallow annular pan 59 is removably supported on the peripheral edge portion of the face plate 27 to catch any babbitt metal which may be spilled at the time of casting.

To heat the parts to which a babbitt bearing is to be applied and the mold, an ordinary blow torch 60 is used, as indicated in Fig. 1. This blow torch 60 is supported from the frame of the machine for vertical and horizontal adjustment by rigidly securing thereto a depending stem 61 turnably and endwise movably mounted in a bearing 62 on the outer end of a two-part arm 63, the members of which are telescopically connected and held in different longitudinal adjustments by a set screw 64. A set screw 65 also holds the stem 61 in different adjustments in the bearing 62. On the inner end of the arm 63 is a bearing 66 turnably mounted on a spindle 67 with freedom for vertical adjustment and held by a set screw 68 in different adjustments thereon. The spindle 67 is carried by a bracket 67^a on the adjacent frame end member 7.

To form independent half babbitt bearings

for the two-part connecting rod end x , divider-acting shims 69 are interposed between the members of said connecting rod end and held by the bolts x' . These shims 69 engage 5 the core sleeve 38 at diametrically opposite points and hold the connecting rod y against pivotal movement on the spindle 46 with its end x' concentric with said sleeve. When a babbitt bearing is cast in a connecting rod 10 having a single piece end, the concentric rings 37 greatly assist the operator in positioning said end on the face plate 27 concentric with the spindle 39. After a babbitt bearing has set, a spanner wrench, not shown, 15 is applied to the hopper flange 43 and turned. The metal in said flange and on the core plate 40 will lock said flange and plate together so that the top plate 40 will turn with the hopper flange 43 and thereby shear the 20 metal at the inner ends of the apertures 44, which is the weakest point. The hopper flange 43 and top core plate 44, together with the waste material therein, may then be lifted from the spindle 39, which is made easy by 25 tapering said spindle. The spindle 46 may be set the correct distance from the spindle 39 by means of a templet or a connecting rod, and after one set, babbitt bearings may be cast in any desired number of connecting 30 rods and each thereof will be identical, the one with the other.

The machine has been described as used in casting a babbitt bearing in a connecting rod from one end thereof. For some connecting 35 rods, it is desirable or necessary to pour the metal into the crank-receiving end thereof through a radial opening therein while the connecting rod is held in an upright position. To thus cast a babbitt bearing, the spring 40 hook 26 is operated to release the track rail 23 and then operate the turntable 16 a one-half revolution and thereafter move the intermediate turntable section 18 on its hinge 20 to carry the parts mounted thereon into 45 the positions shown by broken lines in Fig. 1.

To cast a babbitt bearing in the crank-receiving end of the connecting rod through a radial opening while said rod is held in a horizontal position, the hand wheel 14 is 50 operated to release the table 10 and permit the same to be turned to either side of the frame as indicated by broken lines in Fig. 2.

In Figs. 1 to 4, inclusive, the machine is provided with a mold for casting babbitt 55 bearings directly in connecting rods. In Figs. 5 and 6, said machine is provided with a mold for casting babbitt bearings A in half sections and thereafter applying the same to the parts for which they are 60 intended. This mold includes an upright core box 70 within which is a radially spaced concentric core sleeve 71 which rests on a bottom core plate 72 and is provided with a depending stem 73 which extends 65 through an axial bore in said core plate

and is removably held in the face plate 27 and its hub 28. This core box 70 is radially divided, so that the parts thereof may be separated. On the periphery of the core plate 72 is an annular retaining flange 74 70 adapted to receive and hold the lower end of the core box 70 concentric with the core sleeve 71.

Supported on the upper end of the core sleeve 71 is a top core plate 75 having an 75 axial opening through which projects a stem 76 secured in the upper end of the core sleeve 71 and axially aligned with the stem 73. On the periphery of the core plate 75 is an annular flange 77 adapted to receive the upper 80 end of the core box 70 and hold the same concentric with the core sleeve 71. A hopper flange 78 is removably telescoped onto an extended central portion of the top core plate 75. Molten metal poured into the 85 hopper flange 78 will flow into the mold through apertures 79 in the top core plate 75.

To hold the several parts of the mold shown in Figs. 5 and 6 in assembled relation, there is provided a clamping attachment comprising a pair of upright anchor bars 80 attached to the bar extensions 35 by forming in the lower ends thereof eyes 81, through which said extensions project, and are secured thereto by thumb screws 82. 95 In the upper end portions of the anchor bars 80 is a multiplicity of longitudinally spaced holes 83 adapted to removably hold a pair of cotter pins 84. A clamping bar 85, having at its intermediate portion a hub 100 through which the stem 76 projects, has bifurcated outer ends adapted to receive the anchor bars 80 and bear against the under sides of the cotter pins 84 to connect said bar 85 thereto. Carried by the clamping 105 bar 85 is a pair of clamping screws 86 which impinge against the top core plate 75 on each side of the stem 76 and hold the several parts of the mold assembled.

After the Babbitt metal has set, the same 110 is sheared in the apertures 79 by turning the hopper flange 78 with a spanner wrench, as previously described.

To form the babbitt bearing A in two parts, thin divider blades 87 are interposed 115 between the core box members and engage the core sleeve 71 at diametrically opposite points. In case the babbitt bearing sections stick in the core box 70, the same may be pressed therefrom by screws 88 which have 120 threaded engagement with the sections of said core box.

Referring again to the machine as shown in Figs. 5 and 6, the hopper sleeve 78 is provided with a plurality of internal upright grooves 78^a into which the metal flows to positively prevent said sleeve from slipping on the metal when turned to shear the metal at the inner ends of the apertures 79. A stop pin 7' is secured to the frame 130

7 and arranged to be engaged by the track rail 23 and hold the same in an upright position when the face plate 27 is turned into a vertical position as shown by broken lines in Fig. 1.

During the heating of the connecting rod and the mold, the traveller 51 must be loose on the track rail 23 so as to move during the expansion of the connecting rod to prevent bending of the same.

In case the connecting rod has been bent, one end thereof may be placed over the core sleeve 38 and the other end over the spindle 46, and thus held while being straightened.

The above described invention has, in actual usage, proven highly efficient for the purpose had in view.

What I claim is:

20 1. In a babbittting machine, the combination with a face plate, of a mold on the face plate, and a pan having an open center removably supported on the peripheral edge portion of the face plate.

25 2. In a babbittting machine, the combination with a face plate, of a mold on the face plate, and an angularly adjustable spindle.

30 3. In a babbittting machine, the combination with a face plate, of a mold on the face plate, a spindle bodily adjustable toward and from the mold, and means for angularly adjusting the spindle in respect to the mold.

35 4. In a babbittting machine, the combination with a face plate, of a mold on the face plate, and means for setting the face plate in either a vertical or horizontal position.

5. In a babbittting machine, the combination with a turntable, of a face plate carried by the turntable, and a mold on the face plate.

40 6. In a babbittting machine, the combination with a turntable having a hinged section, of a face plate carried by said hinged section of the turntable, and a mold on the face plate.

45 7. In a babbittting machine, the combination with a turntable having an adjustable hinged section, of a face plate carried by said hinged section of the turntable, and a mold on the face plate.

8. In a babbittting machine, the combination with a turntable having a hinged intermediate section and a top section hinged to said intermediate section, of a face plate carried by the top turntable section, and a mold on the face plate.

9. In a babbittting machine, the combination with a frame, of an angularly adjust-

able table on the frame, a face plate carried by the table, and a mold on the face plate.

10. In a babbittting machine, the combination with a face plate, of a mold on the face plate, a track rail, a traveller mounted on the track rail for adjustment toward and from the mold, and a spindle on the traveller.

11. In a babbittting machine, the combination with a hinged track rail, a face plate carried by the track rail, a mold on the face plate, a traveller mounted on the track rail for adjustment toward and from the mold, and a spindle on the traveller.

12. In a babbittting machine, the combination with a face plate, of a mold on the face plate, a track rail, a traveller mounted on the track rail for adjustment toward and from the mold, a spindle on the traveller, and a scale for setting the traveller predetermined distances from the mold.

13. In a babbittting machine, the combination with a turntable, of a track rail hinged to the turntable, a face plate carried by the track rail, a mold on the face plate, a traveller mounted on the track rail for adjustment toward and from the mold, and a spindle on the traveller.

14. In a babbittting machine, the combination with a turntable, of a track rail hinged to the turntable, means for releasably holding the track rail in a predetermined position, a face plate carried by the track rail, a mold on the face plate, a traveller mounted on the track rail for adjustment toward and from the mold, and a spindle on the traveller.

15. In a babbittting machine, the combination with a frame, of a turntable angularly adjustable on the frame, a track rail hinged to the turntable, means for releasably securing the track rail to the table, a face plate carried by the track rail, a mold on the face plate, a traveller mounted on the track rail for adjustment toward and from the mold, and a spindle on the traveller.

16. In a babbittting machine, the combination with a frame, of a turntable angularly adjustable on the frame, a track rail hinged to the turntable, means for releasably securing the track rail to the table, a face plate carried by the track rail, a mold on the face plate, a traveller mounted on the track rail for adjustment toward and from the mold, and a spindle on the traveller angularly adjustable toward and from the mold.

In testimony whereof I affix my signature.

MORRIS B. MOSER.
